UNITED STATES PATENT OFFICE.

WILLIAM H. MATTHAI, OF BALTIMORE, MARYLAND, ASSIGNOR TO NATIONAL ENAMELING AND STAMPING COMPANY, OF BALTIMORE, MARYLAND, A CORPORATION OF NEW JERSEY.

DESIGN FOR A POULTRY-COOP.

45,392.

Specification for Design.

Patented Mar. 10, 1914.

Application filed December 11, 1913. Serial No. 806,118. Term of patent 14 years.

To all whom it may concern:

Be it known that I, WILLIAM H. MATTHAI, a citizen of the United States, residing at Baltimore, in the State of Maryland, have invented a new, original, and ornamental Design for Poultry-Coops, of which the following is a specification, reference being had to the accompanying drawing, forming part thereof.

Figure 1 is a top plan view, and Fig. 2 is a

side elevation of a poultry coop showing my new design.

I claim,

The ornamental design for a poultry coop, as shown.

WILLIAM H. MATTHAI.
